US00D903613S

(12) **United States Design Patent** (10) Patent No.: **US D903,613 S**
(45) Date of Patent: ** Dec. 1, 2020

(54) **SEMICONDUCTOR MODULE**

(71) Applicant: **ROHM CO., LTD.**, Kyoto (JP)

(72) Inventor: **Ryuichi Furutani**, Kyoto (JP)

(73) Assignee: **ROHM CO., LTD.**, Kyoto (JP)

(**) Term: **15 Years**

(21) Appl. No.: **29/722,317**

(22) Filed: **Jan. 28, 2020**

(57) **CLAIM**

The ornamental design for a semiconductor module, as shown and described.

DESCRIPTION

FIG. 1 is a front, top and right side perspective view of a semiconductor module showing my new design; FIG. 2 is a rear, bottom, and left side perspective view thereof;

FIG. 3 is a front view thereof;

FIG. 4 is a rear view thereof;

FIG. 5 is a top plan view thereof;

FIG. 6 is a bottom plan view thereof;

FIG. 7 is a right side view thereof;

FIG. 8 is a left side view thereof; and,

FIG. 9 is a cross sectional view taken along line 9-9 in FIG. 5.
